(57) **CLAIM**

The ornamental design for folio keyboard for tablet computer, as shown and described.

DESCRIPTION

FIG. 1 is a bottom perspective view of a first embodiment of a folio keyboard for tablet computer showing our new design without a tablet computer included therein;

FIG. 2 is a top perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a bottom perspective view thereof, further including a tablet computer therein;

FIG. 10 is a top perspective view thereof;

FIG. 11 is a top perspective view of a second embodiment thereof without a tablet computer included therein;

FIG. 12 is a top plan view thereof;

FIG. 13 is a bottom plan view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top perspective view thereof, further including a tablet computer therein;

FIG. 19 is a top plan view thereof in a closed position;

FIG. 20 is a bottom plan view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a perspective view of the first embodiment thereof shown in a working position; and,

FIG. 26 is another perspective view of the first embodiment thereof, shown in a second working position.

Broken lines shown in the drawings illustrate portions of the folio keyboard for tablet computer, and form no part of the claimed design.
